AND HIRAM D. CROFT, OF SPRINGFIELD, MASSACHUSETTS, ASSIGNEES TO PERKINS
APPLIANCE COMPANY, OF SPRINGFIELD MASSACHUSETTS, A CORPORATION OF
MASSACHUSETTS.

BROACHING MACHINE.

Application filed February 13, 1922. Serial No. 586,160.

To all whom it may concern:

Be it known that we, JULIAN L. PERKINS, a citizen of the United States of America, and a resident of West Springfield, in the county of Hampden and State of Massachusetts, JOHN OAKLEY, a subject of the King of England, residing at Springfield, in said county and State, and ROBERT A. WILSON and HIRAM D. CROFT, both citizens of the United States of America, and residents of said Springfield, Massachusetts, have invented a new and useful Broaching Machine, of which the following is a specification.

15 Our invention relates to improvements in machines for broaching exteriorly annular or many-sided objects, and more particularly gear blanks to produce gears of a certain type, and consists generally and preferably, 20 with a suitable supporting frame, of twin work holders arranged on opposite sides of the transverse center of the machine, the holders in each pair having an orbital path around a common center, means and mechanism for securing the work on said holders, 25 automatic indexing mechanism for said holders, a pair of broach holders having movement in different directions, and located between the work holders in the two pairs on 30 opposite sides of the aforesaid center, the axes of such broach holders being in the same vertical plane, which plane is in the longitudinal center of the machine and is herein termed the cutting or work plane, and said 35 work holders being capable of having their axes located normally in said plane, and means for securing the cutters or broaches in their holders, together with manually and pedally-operated means or mechanism 40 for effecting or producing certain operations in the machine, and such other parts or members as may be necessary or desirable in order to render the machine complete and serviceable in every respect, all as herein- 45 after set forth.

This is an upright machine and the principal elements thereof are disposed vertically.

One object of our invention is to produce 50 a machine wherewith a plurality or multiplicity of ring gears, such as those that constitute parts of the starters in Ford auto-

mobiles for example, may be cut or broached most expeditiously and at the minimum cost.

A further object is to provide, in a machine of this character, means and mechanism for cutting simultaneously two sets of gear blanks, while at the same time unloading or removing two sets of gears already cut and loading the same number of additional sets of blanks in readiness for broaching, the unloading and loading operations being performed by the operator.

Another object is to afford means for making the roughing cuts in the gear blanks on the stroke of the roughing cutters in one direction, usually the down stroke, and making the finishing cut on the stroke of the finishing cutters in the opposite direction, usually the up stroke, so that at each complete reciprocation of each broach holder a line of finished gear-tooth slots is cut in the set of blanks being operated on. This is possible because the roughing and finishing cutters or broaches are both set in one holder which has a reciprocable movement and an oscillatory movement about its axis as well, said broaches being received in the periphery of said holder in different radial planes thereof, but generally at the same elevation.

Still another object is to provide such a machine that is automatic in the broaching and indexing operations, and in which complete and convenient control by hand and operation of certain elements by foot can be effected in a practicable and efficient manner.

The machine is equipped with all necessary locking devices for movable and adjustable elements, to the end that improper movement at improper times is prevented, and the machine is rendered safe and reliable as well as highly efficient.

Other objects and advantages will appear in the course of the following description.

A preferred embodiment of the invention, whereby we attain the objects and secure the advantages of the same, is illustrated in the accompanying drawings, and we will proceed to describe the invention with reference to said drawings, although it is to be understood that the form, construction, arrangement, etc. of the parts in various aspects are not material, and may be modified.

without departure from the spirit of the invention.

In the drawings, in which similar reference characters designate similar parts throughout the several views, Figure 1 is a top plan of a broaching machine which embodies one form of our invention as aforesaid; Fig. 2, an enlarged, horizontal section through the left-hand half of said machine, taken on line $x-x$, in Fig. 11; Fig. 3, a side or what may be termed front elevation of said machine, with parts of the frame broken out to disclose interior mechanisms; Fig. 4, an end elevation of said machine, with a portion of the carrier therein appearing broken out to show features that would otherwise be hidden; Fig. 5, an enlarged detail of one of the movable dogs associated with or forming a part of the oscillatory mechanism for each broach holder; Fig. 6, a side elevation of the switch-operating mechanism through the medium of which the electric motor (not shown) that drives the broach carriers is reversed; Fig. 7, a detail of the left-hand broach carrier and holder, with the supporting members for said carrier, the parts and members being viewed as in Fig. 4, except that said carrier with said holder is at the lower end of its travel in Fig. 7, instead of at the upper end of its travel as in Fig. 4 and other views; Fig. 8, an enlarged, cross section through one of the broach holders; Fig. 9, a similar section taken at a different elevation from the immediately preceding section; Fig. 10, an enlarged, top plan of a portion of the operating mechanism for one of the broach-holder lock pins; Fig. 11 and 11^a together constitute an enlarged, vertical section through said left-hand half of the machine, in approximately the vertical, longitudinal center or work plane thereof; Fig. 12 is an enlarged, top plan of the index or indexing mechanism for one of the work holders; Fig. 13, an enlarged, top plan of the left-hand, manually-operated and pedally-operated lever mechanism, with which the machine is equipped; Fig. 14, an enlarged, bottom plan of a portion of the base of the frame of the machine, showing the pivots and their bearing lugs for certain of the elements in the aforesaid mechanism, together with the rock-shaft of such mechanism; Fig. 15, an enlarged detail of the rock-shaft lock member; Fig. 16, a side elevation of said mechanism as shown in Fig. 13; Fig. 17, a top plan of the lock segment for one of the work holders; Fig. 18, an enlarged, operative detail of the locking means for the left-hand broach holder, and, Fig. 19, a similar detail but showing the parts and members differently disposed.

The cutting or work plane hereinbefore referred to is on lines $y-y$ in Fig. 1.

65 This is a double or duplex machine

throughout, and the mechanism on either side of the transverse center of said machine is complete in itself or forms a complete unit. The double construction is preferred and used for the sake of economy in building 70 the machine, the compensation or balance obtainable with the broaches when in operation, and the saving in floor space and power. A large saving in floor space is also effected by making a vertical or upright instead of a 75 horizontal machine. It follows that one side of the machine is practically a duplicate of the other side, and that one end of said machine is practically a duplicate of the other end. In view of the conditions just 80 mentioned, it has been deemed necessary to illustrate in detail generally but one-half of the machine, the left-hand half being the one selected. The term left-hand is to be understood as applying to the machine as viewed in Figs. 1 and 3, wherein the ends of the machine are respectively disposed at the left and right of the transverse, vertical, central plane of the machine. Nevertheless, 85 certain central elements that enter into the construction of the left-hand portion of the machine must extend to the right of the aforesaid transverse plane.

In the drawings, the left-hand broach holder is shown at the upper end of its stroke 90 and the right-hand broach holder at the lower end of its stroke, except in the example noted, namely, Fig. 7, and the other elements generally are normally disposed.

The frame of the present machine comprises a base 1 which is designed to rest on the floor, and two uprights 2 having forwardly and rearwardly-extending bottom, plate extensions or flanges 3-3 which are mounted on said base intermediate of its 100 ends and securely bolted thereto, said uprights being connected at the top by a member 4, and having exterior and interior strengthening webs substantially as shown. Some of these webs will subsequently receive special mention. The uprights 2 extend below the floor line, and located under said uprights is a funnel-shaped receptacle 5. The receptacle 5 is open at the top, and this opening is considerably larger in diameter than the space occupied by the depending portions of the uprights 2. The waste oil used to lubricate the parts between the uprights 2 passes downwardly into the receptacle 5, and so also do the chips produced 105 by the cutting operation and the oil used in connection with such operation. The frame also comprises bearing parts and other members of which particular mention will be made when necessary at this description 110 progresses.

For the sake of convenience in describing the machine, and as already intimated, the side illustrated in Fig. 3 will be considered as the front and the opposite side as the rear. 115

Journalled in the uprights 2 and in suitable bearings with which said uprights are provided, in the transverse central plane of the machine, one above the other in the order 5 named, and beginning a short distance above the horizontal plane of the flanges 3, are three horizontal shafts 6, 7, and 8, Figs. 1, 3, and 4. Secured on the forward protruding terminal of the shaft 6 is a gear 9. This 10 gear is designed to be driven from a motor, and a motor pinion or gear 10 and a fragment of a motor shaft 11 are represented in Figs. 1 and 6 but omitted from Fig. 3, said motor gear intermeshing with said first- 15 named gear. Secured on the rear protruding terminal of the shaft 6 is a pinion 12, and this intermeshes with a gear 13 secured on the rear protruding terminal of the shaft 7. Secured on the center of the shaft 8 is a 20 large gear 14, and intermeshing with said gear is a small gear 15 which is secured on the shaft 7, Fig. 11^a. It follows, therefore, that motion imparted to the gear 9 by the pinion 10 is transmitted, through the shaft 25 6, and the pinion 12, the gear 13, the shaft 7, and the gear 15, to the gear 14. The gear 14 causes the cutting or broaching elements to reciprocate, as explained below.

There is a vertical broach carrier 16 arranged to slide up and down in contact with each pair of outer edges of the uprights 2, said carrier being provided adjacent to its outer (front and rear) edges on the inside faces thereof with a pair of V-shaped projections or guides 17 that enter and operate in corresponding grooves in the contiguous edges of said uprights, as best shown in Fig. 2. The carrier 16 is held in place relative to the uprights 2 by means of a pair of 30 vertical gibs 18 bolted to said uprights, all in the usual and well-known manner. On the inside of the carrier 16 in the transverse center thereof is a rack 19, and the gear 14 intermeshes with such rack. There being a 35 rack 19 at each end of the horizontal diameter of the gear 14, the two racks and their carriers 16 are actuated in opposite directions when said gear is rotated. When the gear 14 is rotated in the direction of the associated arrow in Fig. 11, the left-hand carrier 16 is actuated downwardly and the right-hand carrier 16 is actuated upwardly, and, when said gear is rotated in the opposite direction, said first-named carrier is actuated upwardly and said second-named carrier is actuated downwardly. Obviously 45 means must be provided for reversing the gear 14, and such means consists of the customary, automatic, switch and switch-operating mechanism whereby the motor and its shaft 11, which drive the gear 14 and the racks 19 with the carriers 16, are actuated first in one direction and then in the opposite direction, said switch and mechanism operating in the usual and well-known manner.

The switch-operating mechanism comprises a switch-box 20 fastened to the back side of the rear upright 2, a switch-arm 21 projecting from the bottom of said box, a pinion 22 secured to the shaft 8, which latter 70 carries the gear 14 and extends behind said rear upright, and a gear 23 loosely mounted on a horizontal stud 24 that projects from said rear upright above said shaft and between the same and said box, said last-named gear being provided with adjustable dogs 25-25, Figs. 1 and 6. This switch-operating mechanism is so timed that, when one of the carriers 16 arrives at the lower end of its travel, one of the dogs 25 encounters the switch-arm 21 and actuates the same to throw the electric switch (not shown) in the switch box 20 in the direction to cause the motor shaft 11 to be rotated in the opposite direction, and, when the other of said carriers arrives at the lower end of its travel, the other dog 25 encounters said switch-arm from the opposite side and actuates the same to throw said switch for the reversal again of said shaft. At the time either carrier 90 is at the lower end of its travel the other carrier is at the upper end of its travel. With the parts disposed as in Figs. 6 and 11, and the gear 14 revolving in the direction of the associated arrow in the latter view, 95 the shaft 8 revolves the pinion 22 in the same direction with said gear, and so causes the gear 23 to be rotated in the opposite direction, consequently the right-hand dog 25 encounters the switch-arm 21 and throws the same to the left, whereby is brought about the reversal of the parts controlled thereby, by the time the carrier shown in Fig. 11 arrives at the lower end of its travel. Upon the reversal of the revolving members, 100 the left-hand dog 25 encounters the switch-arm 21 and throws the same to the right, or into the position which it occupies in Fig. 6, whereby is brought about another reversal of the parts controlled thereby, such action 105 taking place by the time the carrier in question arrives at the upper end of its travel.

Each broach carrier 16 is provided in the longitudinal center of what may be termed its outer face, or in the side opposite to 115 that whereon one of the racks 19 is located, with a cylindrical broach holder 26, the latter having approximately one-half of its circumference let into an approximately semi-cylindrical opening in the former, Figs. 120 2, 4, 7 and 11. The holder 26 is vertical like its carrier, and has trunnions 27-27 at the top and bottom, which trunnions are journaled in suitable bearing-boxes formed at the ends of said carrier, and completed by 125 upper and lower bearing-caps 28-28 secured by screws to said carrier. Thus mounted the holder 26 is capable of being oscillated on its vertical axis. The oscillatory movement of the holder is produced 130

through the medium of a pair of horizontal, parallel racks 29 slidably arranged on the same plane in the carrier 16 a short distance below the upper bearing-cap 28, teeth forming segmental gears 30—30 cut diametrically opposite to each other in the periphery of the holder 26, and upper and lower cam segments 31 having teeth 31^a on their arcuate edges, loosely mounted on horizontal studs 32—32 that project inwardly from the uprights 2 on the same side of upper and under, intermediate webs 33 and 34 which connect said uprights respectively above and below the gear 14, together with locking and actuating pinions or gears 35—35 mounted on horizontal rock-shafts 36—36 journaled, above and below said studs, in said uprights and projecting beyond the back side of the rear upright—see more particularly Figs. 13 and 16. The rock-shafts 36 at the right of the webs 33 and 34 project beyond the face of the front upright 2. The racks 29 are on opposite sides of the holder 26, and tangential thereto. As shown in Fig. 16 the upper segment 31 is arranged with the teeth 31^a above, and the lower segment 31 with the teeth 31^a below. The edges of the segments 31 which are adjacent to the holder 26 are cam edges and designated by the numeral 37 in each case. The segment teeth 31^a intermesh with the pinions 35. The pinions 35 are held rigidly, by means hereinafter described, and in turn retain the segments 31 in fixed positions with their cam edges 37 in the paths of the inner terminals of the racks 29, such edge of the upper segment inclining upwardly and outwardly, and such edge of the lower sector inclining downwardly and outwardly, from the studs or pivots 32. Inasmuch as the racks 29 are on opposite sides of the holder 26, the segments 31 must be correspondingly disposed in the space between the uprights 2. The upper segment 31 is in the same vertical plane with the rear rack 29, and the lower segment 31 is in the same vertical plane with the front rack 29.

It is now clear, that, when the carrier 16 approaches the lower end of its travel, the inner end of the front rack 29 encounters the edge 37 of the lower segment 31, and is forced outwardly or to the left by such edge. This action causes the holder 26 to be partially rotated to the right in the carrier 16, inasmuch as the front rack 29 is in engagement with the forward segmental gear 30, to an extent corresponding to the length of travel of said rack. At the same time the rear rack 29 is actuated inwardly by the other segmental gear 30 with which said rack intermeshes, so that the latter is in position to encounter the upper segment 31 when the carrier 16 approaches the upper end of its travel. Upon the ascent, therefore, of the carrier 16, the inner end of the rear rack 29 contacts with the edge 37 of the upper sector 31, and said rack is forced outwardly by said edge. The outward movement of the rear rack causes the carrier 26 to be partially rotated to the left to the same extent that it had been previously rotated to the right by the front rack 29, and the latter to be actuated inwardly again. It is seen, therefore, that the left-hand holder 26 has imparted to it approximately a quarter-turn to the right each time it arrives at the end of the down stroke, and a quarter-turn to the left each time it arrives at the end of the up stroke, the reason for which will subsequently become apparent. The amount of rotary movement of the holder naturally depends on the proportions of the segmental gears 30 and the length of stroke imparted by the segments 31 to the racks 29. One-fourth of a revolution is here provided for.

The construction and arrangement of the oscillatory mechanism for the right-hand holder 26 are such as to cause said holder to operate or to be operated on its axis in a similar manner as is the left-hand holder.

It is necessary to lock each holder 26 against rotation at the end of every quarter-turn thereof, and for this purpose a horizontal segment 38 is mounted on the top of the upper trunnion 27 of said holder and rigidly secured thereto, said segment having three openings 39 therein arranged in an arc which is concentric with the arc of the segment, a vertical pin 40 slidably arranged in the head of the carrier 16 for said holder, a yoke 41 at the inner end of an approximately horizontal arm 42 which is secured to the inner terminal of a horizontal rock-shaft 43 journaled in the head of said carrier, a depending arm 44 secured to the outer terminal of said shaft, said last-named arm being provided on the front side at its free terminal with a roll 45, and two movable dogs or cams 46 pivotally connected at 47—47 with plates 56—56 secured to the gib 18 on the left-hand edge of the rear upright 2—see Figs. 1, 3, 4, 5, 7, 10, 11, 18, and 19. The axis of the pin 40 is directly over the arc in which the openings 39 in the segment 38 are located, so that the lower terminal of said pin is adapted to enter any one of said openings. Upper and under bushed bearings 48 and 49, respectively, are provided in the upper part of the carrier 16 for the pin 40, and said part is cut away beneath the under bearing, as represented at 50, to accommodate the inner or arcuate portion of the segment 38. All of these parts and members are outside of the upper terminal portion of the rack 19 with which the carrier 16 is provided, and none can interfere with the reciprocation of said carrier. There is an opening 51 through the carrier 16 above the bearing 49, and in such opening is the yoke 41, a flange 52 on the pin 40, and a spring 53 en-

circling said pin between said collar and the bearing 48. The spring has a constant tendency to force the pin 41 downwardly onto the segment 38, or to retain the lower terminal of said pin in one of the openings 39, said spring acting directly on the flange 52 and forcing the same downwardly on the yoke 41 and the latter onto the top of the bearing 49. When the segment 38 is disposed to receive the lower terminal of the pin 40 in either of the end openings 39 in said segment, the holder 26 is positioned in one or the other of the extreme positions of its oscillatory movement, and, when such segment is disposed to receive such terminal in the intermediate opening 39, said holder is positioned at a point intermediate of the limits of its oscillatory movement, or in neutral position, all due to the relative relation of the segment to the holder. Thus the pin 40 locks the segment 38 and the holder 26 in any one of the three positions.

The arm 42 of the yoke 41 extends rearwardly in the upper part of the carrier 16 to the rock-shaft 43. The rock-shaft 43 is journaled in a bearing 54 that projects to the left from the aforesaid part of the carrier. An opening 55, Figs. 4, 18, and 19, is provided in said part to accommodate the arm 42 and permit the same to be operated. The openings 51 and 55 are in communication with each other. The arm 44 has a normally downward and rearward inclination, and the cams 46 are in the path 25 of the roll 45 with which said arm is provided. There are two of the cams 46 on a side for each arm 44, of which latter there are two in the machine, and such cams are located one above the other in position to be encountered by the roll 45 just before the carrier 16 arrives at the upper and lower ends of its travel, respectively.

Each cam 46 is a member bent intermediate of its ends to form an obtuse angle, and is loosely mounted on one of the pivots 47. Each pivot 47 extends outwardly from one of the plates 56. The plates 56 extend forward beyond the edge of the gib 18 to which said plates are attached, and it is in the projecting parts of said plates that the pivots 47 are set. In the present construction, the plates 56 for the right-hand pivot 47 are fastened to the front forward gib 18 at the right-hand end of the front upright 2. In each case the upper cam 46 depends from its pivot 47, and the lower cam 46 extends upwardly from its pivot 47. A stop pin 57 is set in each plate 56 in position to limit the outward or rearward movement of the free terminal of the adjacent cam 46, consideration being given again to the left-hand cams only. A spring 58 is provided for each cam 46, and said spring has one terminal fastened to the pivot 47 for said cam, and the opposite terminal ar-

ranged to bear against the inner side of the cam. The spring 58 serves to actuate the cam toward the associated pin 57, and normally retain the former in contact with the latter.

When the carrier 16 descends, the roll 45 rides onto the inclined part of the lower cam 46, as said carrier approaches the lower end of its travel, and is consequently carried forwardly or inwardly by said cam and onto the vertical part of the same, and the arm 44 that is provided with said roll is thereby swung inwardly on its pivot 47, and imparts a partial rotation to the rock-shaft 43 in the direction to swing upwardly the arm 42—see full lines in Fig. 18. The arm 42, through the medium of its yoke 41 which bears against the under side of the flange 52, in moving upwardly with the arm 42, carries with it said flange and thus raises the pin 40, against the resiliency of the spring 58. The pin 40 is raised sufficiently to withdraw it from the segment 38. The segment 38 being thus released from the pin 40, is free to move on its axis and so leaves the holder 26 free for the partial rotation directly imparted to it by the front rack 29. By the time the carrier 16 reaches the extreme end of its downward movement, the roll 45 is in position to pass beneath the bottom of the lower cam 46, and the spring 43 immediately acts to depress the pin 40 and thrust the same into the opening 39 in the segment 38 that is the most remote from the opening 39 in which said pin was previously located, so that said segment and the holder 26 are again locked against rotation. When the carrier 16 ascends, the roll 45 is carried upwardly on the outside of the lower cam 46 as indicated by broken lines in Fig. 19, and the latter swings inwardly to enable said roll to continue its upward movement and pass clear of said cam, the spring 58 for said cam yielding to permit of such action and then causing the cam to snap back into contact with its associated pin 57 as soon as the roll clears the cam. Next, as the carrier 16 approaches the upper end of its travel, the roll 45 encounters the inclined portion of the upper cam 46 and rides onto the vertical part of said cam, as illustrated in full lines in Fig. 19, and the pin 40 is again withdrawn to release the segment 48 and the holder 26 in precisely the same manner as before, when the rear rack 29 is caused to act partially to rotate said holder until it assumes its former position. Then the roll 45 passes over the top of the upper cam 46, and the pin 40 descends again into locking position to secure the holder 26 against rotary movement. Upon the descent of the carrier the second time, the roll 45 rides down on the outer side of the upper cam 46, as represented by broken lines in Fig. 180

18, and forces the same out of the way, against the resiliency of the spring 58 that is provided for said cam, until said roll clears said cam, when the latter snaps back 5 into contact with the adjacent pin 57. The roll 45 sets out far enough to clear the ends of the springs 58 that engage the cams 46 contacted with by said roll.

I will next describe the mechanism by 10 means of which the pinions 35 are held stationary, and through the medium of which said pinions may be actuated to throw the segments 31 into neutral position, or into position to cause the holder 26 controlled 15 thereby to be disposed in neutral position. Such mechanism comprises certain connecting-rods and operating levers, and is connected with other connecting-rods and operating levers which are associated with the 20 work-holding mechanism of the machine.

Referring more particularly to Figs. 13 and 16, it will be seen that the rock-shafts 36, upon which are mounted the two gears 35 that control the sectors 31 by means 25 of which the racks 29 that engage the left-hand holder 26 are operated, are provided on their rear terminals, which terminals extend beyond the back upright 2, with arms 59 and 60, the first of these arms being 30 carried by the upper rock-shaft and the second by the lower rock-shaft. The arm 59 extends downwardly to the right from the upper rock-shaft, and the arm 60 extends downwardly to the left from the 35 lower rock-shaft. A connecting-rod 61 has each end pivotally attached at 62 to the arms 59 and 60, the upper terminal of said rod being connected with the free terminal of said first-named arm, and the lower 40 terminal of said rod being connected with said second-named arm intermediate of its ends. The construction and arrangement of the parts are such that, if the connecting-rod 61 be raised, the arms 59 and 60 are swung 45 upwardly so as to carry the pivots 62 through corresponding arcs and actuate each rock-shaft 36 to the same extent that the other rock-shaft is actuated, and to actuate said rock-shaft and the gears 35 in 50 opposite directions. The upper gear 35 is actuated to the left and the lower gear 35 to the right, with the result that the segments 31 are swung to the right or inwardly 55 on their pivots 32. When the sectors 31 are thus inwardly disposed, by elevating the connecting-rod 61, whichever of the racks 29 contacts with its associated segment is actuated to the left or outwardly only far enough to impart to the holder 26, with 60 which said rack is in engagement, a rotary movement the extent of which is about one-half of that normally imparted to said holder by the rack. In this manner and by this means the holder is caused to assume an 65 inactive or neutral position, the reason for

which will hereinafter be made manifest. The movement which the gears 35 impart to the sectors 31 is not sufficient to remove the cam edges 37 of said sectors entirely from the paths of the racks 29, but enough 70 to reduce to the required extent the travel imparted to said racks by said edges. Upon actuating the connecting-rod 61 downwardly into its former position, the arms 59 and 60 and the parts and members operated thereby 75 are returned to normal position.

Normally, the near rack 29 moves from the dotted-line position to the full-line position shown in Fig. 16, as said rack moves or is carried upwardly, and a similar action 80 occurs when the front rack 29 encounters the lower segment 31, in the downward movement of said front rack. These movements are cut down or shortened when the segments 31 are swung inwardly so as to 85 project less into the paths of the racks, or so as to present to said racks cam surfaces which are more nearly erect.

Each of the connecting-rods 61 is raised 90 and lowered by means of a manually-operated lever 63 which is pivotally connected at 64 either with the oblique web (188) that extends rearwardly and to the left from the back upright 2, or with the oblique web (189) that extends forwardly and to the right from the front upright 2. The pivot 64, for the lever 63 that operates the connecting-rod 61 associated with the left-hand holder 26, is set in the web 188, while the 95 other pivot 64 is set in the web 189. Each 100 of the aforesaid webs is provided with a sector 65 in which there are two radial openings 66, as shown in Fig. 16. The inner terminal of each lever 63 is forked as shown 105 at 67, and such terminal embraces the associated connecting-rod 61 between two flanges 68 thereon. Said lever is provided with a latch-rod 69, adapted at its inner terminal to enter either of the openings 66 in the 110 sector 65. A keeper 70 is provided on the lever 63, adjacent to the sector 65, to serve as a guide for the latch-rod 69. At the outer end of the lever 63 is a handle 190. The outer end of the latch-rod 69 is connected with a latch 71 which is pivotally connected at 72 with the lever 63, adjacent to the handle 190. The latch 71 is extended outwardly alongside of the handle 190, and a spring 73 is interposed between the extended part of the latch and said handle, so 115 that said part is normally held away from said handle, and the rod 69 permitted to enter into locking engagement with the sector 65.

When the inner end of the latch-rod 69 is 120 in the upper opening 66, the connecting-rod 61 is thereby locked in its low position, in which position the parts are disposed and held in such a way as to present the cam edges 37 of the segments 31 at their sharpest 125 130

incline to the racks 29. Before the connecting-rod 61 can be raised for the purpose of throwing the holder 26 controlled thereby into neutral position, it is necessary to grasp 5 the handle 190 with the extended part of the latch 71, and force such part, against the resiliency of the spring 73, toward said handle, whereby said latch is rocked and the latch-rod 69 drawn out of the upper opening 10 66. The lever 63 can now be rocked on its pivot 64 to raise the terminal 67 thereof and with it the connecting-rod 61. After thus elevating the connecting-rod 61, the latch 71 is released to its spring 73, and the 15 latter acts to return said latch to normal position and actuate the latch-rod into the lower opening 66. The lever 63 is now locked in its new position, and with it the connecting-rod 61 in elevated position, 20 and the holder 26, as the same is moved up and down by the carrier 16 provided therefor, remains in neutral position. Upon again grasping the handle 190 and withdrawing the latch-rod 69 from the lower 25 opening 66, and rocking the lever 63 downwardly at the forked end, to lower the connecting-rod 61 and permit said latch-rod to enter the upper opening 66, the parts and members are again disposed in such a manner 30 that the holder 26 is oscillated to the full extent by the racks 29.

A bell-crank-lever 74 is pivotally attached at 75 to the back side of an intermediate wall of the base 1, below the horizontal plane of the free terminal of the arm 60 above, at the left of the transverse, vertical, central plane of said base, and another bell-crank-lever 74 is similarly attached to the front of said wall below the horizontal plane 35 of the free terminal of the other arm 60, at the right of said vertical plane, Figs. 3, 13, and 16. A connecting-rod 76 has its upper terminal pivotally attached at 77 to the free 40 end of the arm 60 above, and its lower terminal pivotally attached at 77 to the inner terminal of the associated bell-crank-lever, there being such a rod between each arm 60 and the bell-crank-lever below. The bell-crank-levers 74 are arranged with their 45 angles uppermost, and the angular portion of each is the part mounted on the pivot 75 provided for the same. There is a horizontal bearing 78 for each pivot 75, which bearing extends from the aforesaid intermediate wall 50 of the base, such wall being indicated by the numeral 79. A transverse rock-shaft 80 is journaled in bearings 81 and 82 in each end portion of the base 1, as shown in Fig. 14. Secured to the outer end or terminal of each 55 of these rock-shafts is an upstanding arm 83, and a connecting-rod 84 extends between said arm and the short arm of the adjacent bell-crank-lever 74, such bell-crank-lever being arranged in each case with its short arm 60 extending toward the adjacent end of the

base 1 and its long arm extending toward the central, transverse, vertical plane of said base. Each connecting-rod 84 is approximately horizontal and has its ends pivoted at 85—85 to the contiguous arm 83 70 and the short arm of the contiguous bell-crank-lever, respectively. Each rock-shaft 80 has an offset 86 therein, the transverse center of which is in the work plane y—y of the machine. 75

The rock-shaft 80 and its connections for each end of the machine, are so arranged that, when the associated connecting-rod 61 is in its depressed and normal position, the associated connecting-rod 76 is also in its 80 depressed position, and the offset 86 is disposed vertically. Upon elevating the connecting-rod 61 and, through the medium of the arm 60, the connecting-rod 76, the bell-crank-lever 74 is actuated to draw inwardly 85 the connecting-rod 84, and thus partially to rotate the rock-shaft 80 in the direction to carry the offset 86 from the vertical into an approximately horizontal position. A reversal of the movement of the connecting-rod 90 61 brings about a reverse movement of the intervening parts and members between said rod and the rock-shaft 80, and actuates the latter in such a manner as to return the offset 86 to vertical position. The offset 86 95 serves as a lock for a pin 87 that will subsequently be described.

Associated with the connecting-rod 84 and the rock-shaft 80 in each end of the base 1, although not directly connected 100 therewith, are an approximately horizontal treadle 88, and two approximately horizontal levers 89 and 90. The treadle 88 is pivotally connected at 91, intermediate of its ends, with a pair of lugs 92 with which each end portion of the base is provided on the inside; the lever 89 is pivotally connected at 93 with a pair of lugs 94 with which said end portion is also provided on the inside; and the lever 90 has its inner 105 end pivotally connected at 95 with a pair of lugs 96 with which said end portion is further provided. Each treadle 88 extends outwardly through a slot in the adjacent end of the base, and is provided at its 110 outer terminal with a foot-piece 97. The outer end of the lever 89 has an universal- or ball-joint connection 98 with the inner end of the treadle 88, and an universal- or ball-joint connection 99 is provided between the outer end of the lever 90 and said treadle adjacent to the pivot 91 and between said pivot and said first-named ball-joint connection. The inner terminal of the lever 89 is forked, as shown at 100. The lever 115 90 is provided on top adjacent to the pivot 95 with a disk or plate 101 which constitutes what may be termed a stirrup.

The treadle mechanisms and the rock-shafts 80 with their offsets 86 are associated 120 125 130

with work-holding mechanisms that are mounted on the base 1 at both ends above said first-named mechanisms and said rock-shafts. The purpose and operation of the treadle mechanisms and the rock-shafts 80 will, therefore, be left for consideration in connection with the work-holding mechanisms.

Referring next more particularly to Figs. 10 2, 4, 8, 9, and 11, it will be seen that the broach-holder 26 therein shown has a large, longitudinal recess or opening 102 in one side thereof, and that such opening is adapted to receive a pair of vertical L-shaped bars 103, and a plurality of horizontal lock blocks 104. Each bar 103 has a broad arm and a narrow arm. One of the bars 103 carries a plurality of roughing cutters or broaches 105 and the other of said bars 20 103 carries a plurality of finishing cutters or broaches 106, there being in the present example four of each.

The roughing broaches 105 are positioned to cut on their down stroke, and arranged 25 with one face of each against the broad arm of one of the bars 103, and with their inner edges against the narrow arm of the bar, and are initially secured to said bar by means of screws, such as those shown at 30 107 in Fig. 9. Each screw 107 is introduced into an oblique recess 108 in the outside of the bar 103, and tapped into one of the broaches, sufficient stock being left at the inner end of said recess to afford 35 ample support for said screw. There may be provided three, more or less, screws 107 for each broach 105.

The finishing broaches 106 are positioned to cut on their up stroke, and set into and 40 secured to the other bar 103 in substantially the same manner and by substantially the same means as have been described in connection with the roughing broaches 105.

The bars 103 are arranged in the opening 45 102 with the roughing and finishing broaches (105 and 106) adjacent to each other, the outer sides of the broad arms of said bars bearing against the approximately radial sides of said opening, and the innermost surfaces of said bars or of the short 50 arms thereof bearing against suitably cut surfaces in the innermost part of said opening substantially as shown. Thus each bar 103 bears with two surfaces on the holder 55 26. Screws, such as those appearing at 109, are employed to assist in holding the bars 103 in the positions just described, and the broaches in place in said bars. Each screw 109 is introduced into a recess 60 110 that opens through the periphery of the holder 26, and tapped into and through the adjacent bar into one of the broaches carried by the bar. Sufficient stock is left 65 at the inner end of each recess 110 to afford ample support for the screw 109 located

in such recess, and said screw enters the bar 103 and the broach at right-angles thereto.

The lock-blocks 104 afford additional means for retaining the broaches 105 and 70 106 in place in their bars 103 and the latter in place in the holder 26. There may be any required number of these blocks—in the present case there are five of the same, and these are located one adjacent to the upper 75 ends of the upper broaches, another adjacent to the lower ends of the lower broaches, and the others across the joints between said broaches. Each block 104 is secured in place by means of a bolt 111 which passes through 80 said block and the space between the same and the transverse side of the opening 102, to be tapped into the holder 26, said bolt being radial to said holder. When the bolt is in place and tightened, it forces its block 85 104 tightly between the roughing and finishing broaches with which the ends of said block contact, and thus wedges said block in place and securely holds said broaches and their bars 103 in the holder 26, supplementing 90 the screws 109 and 107. It is necessary that the roughing and finishing broaches be secured so firmly in the holder that there can be absolutely no independent movement of said broaches, and to this end 95 the fastening and securing means described above have been provided.

The size of the opening 102 in the carrier 26, and the size, construction, and arrangement of the bars 103 and the broaches 100 105 and 106 are such that, when said holder is located at either end of its maximum rotary movement, either the roughing broaches or the finishing broaches are located with 105 the central, longitudinal, vertical plane common thereto in the work plane y—y, so that normally either the roughing broaches or the finishing broaches are in said work plane. The aforesaid plane of either set of broaches is also radial to the holder.

The securing means for the broaches in the right-hand holder 26 are precisely the same as those for the broaches in the left-hand holder 26, which latter have been fully described.

The roughing broaches 105 do their work on the down stroke of each of the holders 26, and the finishing broaches 106 do their work on the up stroke of each of said holders. The carriers 16 for said holders constantly travel in opposite directions, and, under the present arrangement, when the roughing broaches carried by one holder are making their cut the finishing broaches carried by the other holder are making their cut, and vice versa. This is made possible by locating the two upper segments 31 in the paths of the two rear racks 29 and the two lower segments 31 in the paths of the two front racks 29, because by so doing both 125 130

holders 26 are actuated in the same direction upon arriving at either end of their stroke, it being understood that, when the roughing broaches carried by one holder are 5 in the work plane, the finishing broaches carried by the other holder are in the same plane, while the inactive finishing broaches are in front of said plane and the inactive roughing broaches are behind said plane, 10 and the reverse is true when the holders are shifted—see Fig. 1.

The cutting edges or teeth of all of the broaches project beyond the periphery of the holder 26 and beyond the outer ends of the 15 bars 103.

It will now be seen that, when the machine is in operation, one set of roughing broaches and one set of finishing broaches are constantly in the work plane, and that 20 at the end of each simultaneous up and down stroke of the carriers 16 the holders 26 are shifted to take out of said plane the sets of broaches which have just completed their cutting operation and to move into 25 said plane the other sets of broaches. Except for the instant at the ends of the travel of the carriers 16, when the holders 26 are shifted on their axes and said carriers reversed, one set of roughing broaches and one 30 set of finishing broaches are in the work plane and making their cuts, provided there is work in position at each end of the machine to be operated on by said broaches.

There are two supporting and carrying 35 elements for the work at each end of the machine, and provision is made for transposing the positions of the same so that either can be located in operative position relative to the adjacent holder 26. We will 40 now describe the aforesaid elements at the left-hand end of the machine, with the understanding that corresponding elements are provided at the right-hand end. Special reference is to be had to Figs. 1, 2, 3, 4, and 45 11 and 11a.

A normally-stationary turn-table 112 is mounted on the base 1. The turn-table has a central, vertical shaft 113 which is journaled directly above the stirrup 101 located 50 in said base at the left-hand end thereof, in a bearing 114 in the base 1, a ball-bearing 115 being interposed between said stirrup and the bottom of said shaft. The portion 55 of the shaft 113 that is in the bearing 114 is larger than the portion of said shaft upon which the turn-table 112 is directly mounted, so that a shoulder 116 is formed on said shaft. Normally the turn-table 112 rests directly on top of the base 1, and the shoulder 116 is then in the same plane with said top. The axis of the shaft 113 is in the work plane of the machine. The turn-table 60 may or may not be rigidly attached to the shaft 113, just as is preferred.

Rising from the turn-table 112, on oppo-

site sides of the shaft 113, are two vertical shafts 117. Each shaft 117 has a screw-threaded base with which a nut 118 is connected to anchor said base in the turn-table. Within the aforesaid base of each of the 70 shafts 117 in the axial center thereof is an opening 119. The opening 119 in either shaft is adapted to receive the upper terminal of the lock pin 87. When either shaft 117 is engaged by the pin 87, such shaft and 75 its companion are located with their axes in the work plane y—y. The pin 87 is in position to engage the inner shaft 117, which is the shaft upon which the holder for the work actually being operated on is mounted, 80 or is a part of such holder.

The pin 87 is slidably arranged in a hollow member 120 that depends from the top of the base 1 in the work plane y—y, and to the right of the bearing 114 or between such 85 bearing and the transverse, central, vertical plane of the machine. The pin 87 is provided with a stem 121 that extends downwardly from the bottom of said pin and through the bottom of the member 120, there 90 being a head 122 on the lower end of said stem. A spring 123 is interposed between the bottom of the pin 87 and the bottom of the main passage in the member 120, and normally actuates said pin upwardly and 95 retains it in engagement with the shaft 117 above. The rock-shaft 80 is so located that, when its offset 86 is vertically disposed, the same is directly beneath the head 122 of the stem 121, so that said stem and the pin 87 100 can not be forced downwardly. The fork 100 of the lever 89 engages the stem 121 above the head 122.

In order to rotate the turn-table 112 about its axis, for the purpose of changing the 105 relative positions of the work holders of which the shafts 117 constitute parts, or, in other words, to interchange the positions of said shafts, it is first necessary to unlock said turn-table by withdrawing the pin 87 from 110 the opening 119 in the right-hand shaft, and then raise said turn-table with the work 115 holders on the shoulder 116 from the base 1. These results are accomplished by grasping the handle of the associated lever 63 and actuating said lever to withdraw the offset 86 from beneath the head 122, and placing the foot on the part 97 of the treadle 88 and actuating said treadle to rock upwardly the 120 connected terminals of the levers 89 and 90. Since the connection 98 is farther from the pivot 91 than is the connection 99, and the fulcrum of the lever 89 is nearer said connection 98 than is the fulcrum of the lever 90, the forked terminal 100 of said lever 89 125 moves more quickly and through a greater space than does the stirrup 101 which is on the lever 90 quite near to the inner fulcrumed terminal of the same, when the portion of said treadle with which said levers 130

are connected is elevated. Consequently the first effect of the depression of the outer terminal of the treadle 88 is to rock the lever 89 in such a manner as to carry the fork 5 100 thereof downwardly and so withdraw the pin 87 from engagement with the shaft 117 above, through the medium of the head 122 and the stem 121, and against the resistance of the spring 123, which action is 10 possible because the offset 86 is now out of the way of said head. And the second effect of the motion imparted to the treadle is to raise the lever 90 and the stirrup 101. The upward movement of the stirrup 101 is 15 transmitted through the ball-bearing 115 to the shaft 113, and the latter is elevated and carries up with it the turn-table 112 and all of the parts and members supported thereby. The upward movement of the shaft 113 is 20 comparatively slight, being only sufficient to raise the turn-table 112 clear of the top of the base 1. With the turn-table thus elevated the same can be rotated on and with the shaft 113 on the ball-bearing 115.

25 The same movement of the lever 63 which actuated the offset 86 out of the perpendicular, also caused the left-hand holder 26 to be actuated into neutral position, with the roughing and finishing broaches carried by 30 said holder disposed on opposite sides of the work plane $y-y$. Although the lever 63 can be operated at any time, the holder 26 is not actuated into full neutral position until it arrives at one end or the other of its 35 vertical travel. While in neutral position the holder can continue to move up and down without the broaches contacting with the work.

40 After the turn-table 112 has been given by hand a half revolution, the treadle 88 is released, and said turn-table settles down again by gravity onto the base 1, and the spring 123 forces the pin 87 upwardly into the opening 119 in the base of the newly- 45 presented shaft 117. The lever 63 is then operated to restore the offset 86 to its up-right position beneath the head 122, and to permit the holder 26 to assume one of its operative or cutting positions.

50 Each shaft 117 is the axis of a work holder, and mounted on such shaft is such work holder which comprises, besides said shaft, a horizontal base 124, a horizontal plate or disk 125, a vertical cam sleeve 126, 55 six segmental, vertical separators or spacers 127, the same number of vertical friction bars 135, a horizontal head 128, and six, long, vertical rods 129 and nuts 192 therefor, together with certain other parts and 60 members yet to be described, as illustrated more particularly in Figs. 11 and 11^a. A ball-bearing 130 is interposed between the turn-table 112 and the base 124, so that the latter may revolve freely on the former.

65 The cam sleeve 126 has a worm-wheel 131 secured to the base thereof, and said sleeve is shouldered at 132 to receive beneath the shoulder the edge of the opening in the plate 125 provided for the passage of that portion of the sleeve which is between said shoulder and the worm-wheel 131. The worm-wheel 131 is received and operates in a central opening 133 in the top of the base 124. Also in said opening is a worm 134 which intermeshes with the worm-wheel 131. The 70 plate 125 rests on the base 124 above the worm-wheel 131, and the separators 127 and friction bars 135 rest at their lower ends on said plate. The head 128 is on top of the cam sleeve 126 and the spacers 127. Each 75 separator has two radical arms 136, and one of the rods 129 is located between such arms, and there are top and bottom, horizontal flanges or webs 137 and an intermediate, horizontal flange or web 138 which extend 80 between and connect said arms, and through which said rod passes. The rods also pass through a flanged portion of the cap 128 and the plate 125 to be tapped into the base 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

cially with the sleeve 126 and its shaft 117. The spacers are clear of the cams 144.

Each clamp 141 is an angular member adapted to bear with the bottom edge of its 5 vertical part on the uppermost blank 139, and with its horizontal part on the flange of the head 128, said horizontal part being slotted at 145 to accommodate one of the rods 129 below the upper end of the same. After 10 the blanks 139 have been stacked to the required height, or until approximately level with the tops of the spacers 127, the clamps 141 are slipped into place beneath the nuts 192 on the rods 129, with the depending parts 15 of said clamps bearing on the top of the uppermost blank, and said nuts are screwed down tightly onto said clamps, thus forcing the latter hard against the blanks. Inasmuch as the rods 129 are screwed into the 20 base 124, when the nuts 192 are screwed down tightly, all of the members through which said rods pass are securely tied together. The binding force now exerted by the clamps 141 on the blanks 139, added to 25 the frictional engagement existing between the bars 135 and said blanks, causes the latter to be so securely and rigidly held in place on their supporting members that any movement of any blank independent of the 30 holder is rendered impossible.

The flange of the head 128 may be cut away, as shown at 146, to leave a raised rim 147, Figs. 2 and 11, upon which the inner ends of the clamps 141 bear. This construction insures the desired forcible contact of the clamps 141 with the stack of blanks 139 when the nuts 192 are tightened.

After the blanks 139 have been cut and formed into gears, they are released so that 40 they can be removed from their holder, by loosening the nuts 192 and removing the clamps 141, and revolving the worm 134 in the direction to rotate the worm-wheel 131 to the right. The rotation of the worm- 45 wheel 131 to the right, and the consequent rotation in the same direction of the cam sleeve 126, removes the pressure from the inner edges of the bars 135 and loosens said bars sufficiently to enable the completed 50 gears to be lifted off of the holder.

The arms 136, which form guides for the friction bars 135, fall short of the blanks 139 when the latter are concentrically disposed, while the throw that may be imparted 55 to said bars by the cams 144 is sufficient to project said bars beyond the inner circumference of said blanks.

After the blanks 139 have been placed in 60 position on their holder and clamped thereto, it is necessary to supply the upper end of the shaft 117 of such holder with a bearing, wherefore a horizontal, vertically-movable yoke 148 is provided. There 65 are two yokes 148, and with each is incorporated the indexing mechanism for the

holder and its blanks below. Such mechanism consists in part of a disk 149 having an upwardly-extending sleeve 150. The disk 149 and its sleeve are bored to fit the upper terminal of the shaft 117, and said sleeve is 70 screw-threaded at the top to receive a nut 151. The disk 149 when in operative position rests on the head 128. The central portion or hub of the yoke 148 is embraced between the nut 151 above and a ball-bearing 75 152 below, which latter is interposed between the disk 149 and said hub. The disk 149 is, therefore, free to rotate beneath the hub of the yoke 148 and on or with the shaft 117. The above-mentioned parts and members can be seen to good advantage in Figs. 1, 2, 3, 4, 11, and 12.

In the present example the shafts 117 are loosely journaled and thus able to rotate, and the parts and members mounted directly on 80 said shafts are free thereon so that independent movement between them and the shafts is possible, but it is obvious that said shafts might be secured against rotation in their bearings, or said parts and members might 85 be secured to said shafts, since the required results in any case would be obtained.

The head 128 has two oppositely-disposed lugs 153, from which rise two posts or studs 154. The protruding portions of the studs 154 are tapered in part and end in screw-threaded terminals at the top. Tapered openings, one of which appears at 155 in Fig. 12, are provided in the index disk 149 to receive the protruding portions of the studs 154. Nuts 170, Figs. 3 and 4, are screwed onto the studs 154 above the disk 149. It is now clear that rotary motion imparted to the disk 149 must be communicated to the head 128 and rigidly attached parts and 100 members, including the blanks 139.

Referring more particularly to Figs. 2, 3, and 4, it will be seen that forwardly- and rearwardly-extending wings 156 are provided on oblique webs at opposite ends of the 105 uprights 2, and that these wings, together with gibbs 157—157 which are bolted to the faces of said wings, afford vertical ways or guides for the inner terminals of the arms of the yokes 148, such terminals of the left-hand yoke being indicated at 158—158 in Fig. 2, and there appearing also in this view vertical, V-shaped guides 159—159 that fit and slide in corresponding grooves in said 110 wings.

Each yoke 148 is counterweighted. Two cables 160 are attached at their lower terminals to the arms of the yoke, and counterweights 161—161 are attached to the other terminals of said cables, the latter 125 passing over idlers 162—162 that are loosely mounted on horizontal studs 163—163 supported at the proper angles by bearings 164—164 which project from the outer faces 130 of the uprights 2 adjacent to their vertical

edges at one end or the other. The counterweights 161 enable the yoke 148 to be moved up and down with the application of comparatively little power.

- 5 On the inner face of that portion of the rear yoke arm that slides between the rear wing 156 and the rear gib 157 a vertical rack 165 is provided, and a short shaft 166 is journaled in the back edge of said wing, 10 and has secured thereon a pinion 167 which intermeshes with said rack, Fig. 2. A crank 168 is secured to the rear terminal of the shaft 166, which terminal extends rearwardly beyond the back wing 156. These 15 parts and members are at the left-hand end of the machine behind, and duplicate parts and members are at the other end of the machine in front, as shown in Fig. 3. When the crank 168 is turned in one direction, the 20 yoke 148 is elevated, through the medium of the shaft 166, pinion 167, and rack 165, and when said crank is turned in the opposite direction said yoke is lowered, through the same medium as before.
- 25 In order to lock each yoke at any desired elevation, or secure the same against possible accidental descent, a lock-screw 169 is tapped into the outer face of the rear (or the front) gib 157 and adapted to bear with 30 its inner terminal against the corresponding face of the adjacent yoke terminal 158. This lock-screw is provided with the usual handle. When the lock-screw 169 is turned inwardly to bear forcibly against the yoke 35 terminal 158, it prevents the yoke from moving downwardly, but upon loosening said screw the yoke may be freely moved in either direction. The two lock-screws 169 appear in Figs. 1, 2, 3, and 4.
- 40 After the blanks 139 have been placed in position on and secured to the holder, the yoke 148 with the index mechanism for said holder is let down, by means of the pinion 167 and rack 165, over the shaft 117 and 45 onto the head 128 of said holder, said shaft being received in the disk 149 and its sleeve 150. At this time it may be necessary partially to rotate the disk 149 so as to bring the openings 155 in said disk into line with 50 the studs 154 below, in order that, as the yoke descends, said studs shall enter said openings and permit said disk to come to rest on top of the head 128. Two of the nuts 170 are then screwed onto the studs 154 55 above the disk 149. After the yoke has been lowered into operative position, it is secured by means of the lock-screw 169.
- 60 After the blanks 139 have been broached and converted into gears, the nuts 170 are taken off, the lock-screw 169 is loosened, and the yoke 148 with the index mechanism is raised clear of the holder, upon which said gears are mounted, into the position such as that indicated by dotted lines (for 65 the right-hand yoke) in Fig. 3. The turn-

table 112 is then operated to move the aforesaid holder from beneath the yoke, and the gears are removed from the holder.

Although the yoke is in a sense a part of the work holder and also in a sense a part 70 of the index mechanism, it is herein treated as a distinct or independent member, inasmuch as the offices of the same are to center the upper terminal of the work-holder shaft and carry the index mechanism, being itself 75 with said mechanism removable from and replaceable on said holder.

Each yoke supplements the associated lock-pin 87 in preventing the turn-table below said yoke from rotating. 80

For a clear understanding of the index mechanism particular reference may be had to Fig. 12, wherein is illustrated the index at the left-hand end of the machine. Therein are shown a fragment of the disk 149, 85 which is provided with peripheral lock-teeth 171, and a fragment of a ring 172 having on its periphery ratchet-teeth 173 that are set inwardly a little from said lock-teeth, a horizontal arm 174 provided on the rear edge 90 with teeth 175 that are adapted to intermesh with said first-named teeth, and a horizontal pawl 176 having on the left-hand edge near the free terminal thereof teeth 177 that are adapted to engage with said ratchet- 95 teeth. The outer terminal of the arm 174 is pivotally connected at 178 with a bearing boss or lug 179 on the underside of the left-hand yoke 148, and said arm is provided at its inner terminal with a roll 180. The roll 100 180 is in the path of a cam-block 181 secured to and carried by the adjacent carrier 16, see Figs. 1, 7, and 12. The cam-block 105 181 for the left-hand index is attached to the outer face of the carrier 16 adjacent to the forward gib 18, near the bottom of said carrier, so that, when the latter ascends and as it approaches the end of its upward travel, said cam-block encounters the roll 180 and swings the index arm 174 forwardly on its 110 pivot 179, against the resiliency of a spring 182 interposed between the front edge of said arm and a lug 183 projected inwardly from the front arm of the left-hand yoke near the inner end thereof; and, when said 115 carrier descends and said block passes away from said roll, said index arm is actuated rearwardly on said pivot by said spring. The teeth 175 are located a short distance from the pivot 178, and between said teeth and the roll 180 is a vertical stud 184 which is set in the top of said arm. The pawl 176 extends rearwardly from the arm 174, and is provided adjacent to its forward end with a slot 185 to receive the stud 184. A spring 120 186 is arranged between the arm 174 and the pawl 176 in such a manner as to actuate the latter toward the ring 172 and retain the teeth 177 in engagement with the ratchet-teeth 173. The ring 172 is let into an an- 125 130

nular peripheral channel in the top of the disk 149, and secured therein to said disk. Two guard rings 187 are attached to the disk 149 and ring 172 above and below the lock-teeth 171 and the ratchet-teeth 173, respectively, and extend a short distance beyond said teeth to protect the same from chips and dirt that might otherwise come into contact with said teeth as the broaches 10 ascend and descend during the cutting operation.

Normally the stud 184 is somewhat remote from the front end of the slot 185, consequently the first effect of the forward movement imparted to the arm 174, by the cam-block 181, is to withdraw the teeth 175 from the lock-teeth 171 and thus unlock the disk 149. Then the stud 184 encounters the front end of the slot 185, and, through the medium of the pawl 176 with its teeth 177, which latter engage the ratchet-teeth 173, causes the disk 149 with the work holder and work below to be partially rotated. The movement thus imparted to the disk and work holder is equal to the distance between two adjacent tooth slots cut or to be cut in the blanks 139. When the arm 174 swings backwardly again under the influence of its spring 182, after being released by the cam-block 181, the teeth 175 first engage the lock-teeth 171 and so cause the disk 149 and the work holder and blanks below to be held against further rotation on the axis of said holder, and then the stud 184 is carried rearwardly away from the front end of the slot 185 and into contact with the rear end of said slot, and actuates the pawl 176 rearwardly, the pawl teeth 177 clicking past the ratchet-teeth 173, until said teeth 177 have 40 made a new engagement with said ratchet-teeth in readiness for the next indexing operation. The slot 185 must be of sufficient length to enable the teeth 175 to be disengaged entirely from the lock-teeth 171, at 45 the time the arm 174 is swung forward.

The parts and members which make up the right-hand indexing mechanism are in reverse position relative of the parts and members of the indexing mechanism just 50 described.

The complete operation of the machine as a whole, starting with the parts and members disposed as shown in the general views, is briefly described as follows:

55 Assuming that the gear 14 is rotating to the left, the left-hand carrier 16 travels downwardly and causes the roughing broaches 105 in the holder 26 mounted in said carrier to cut a vertical channel through the gear blanks 129 on the left-hand work holder, and at the same time the right-hand carrier 16 travels upwardly and causes the 60 finishing broaches 106 in the holder 26 mounted in said last-named carrier to com-

plete the vertical channel last cut by the roughing broaches in said last-named holder. If no channel has yet been cut by the roughing broaches in the right-hand holder, said holder should be caused to assume the neutral position during the first upward stroke of its finishing broaches. At the end of the down stroke of the left-hand carrier 16, the holder 26 therein is unlocked, by the withdrawal of the associated pin 40, partially rotated to the right, through the medium of the front rack 29 which is in engagement therewith, and the bottom segment 31 which is in the path of said rack, to position the finishing broaches 126 in said holder in readiness to complete the channel or slot just previously cut in the blanks when the holder ascends, and relocked by said pin; and at the end of the up stroke of the right-hand carrier 16, the holder 26 therein is unlocked, partially rotated to the right, through the medium of the rear rack 29 which is in engagement with said last-named holder, and the bottom segment 31 which is in the path of said last-named rack, to position in the work plane $y-y$ the roughing broaches 105 with which said last-named holder is equipped, and relocked. In the event the first roughing cut has not been made in the blanks carried by the active, right-hand work holder, the lever 63 is operated to move the right-hand segments 31 out of their neutral positions, before the right-hand carrier 16 arrives at the end of its upward travel. The switch arm 21 is now actuated to bring about the reversal of the gear 14, and the left-hand carrier is caused to ascend and the right-hand carrier to descend, whereby the roughing cut made in the left-hand blanks 139 is finished, and a roughing cut is made in the right-hand blanks 139. After the finishing broaches at the left clear the blanks, and as the left-hand carrier arrives at the upper end of its travel, the holder carrying said blanks is indexed, through the medium of the left-hand cam-block 181, and the arm 174, pawl 176, and other associated parts and members of the left-hand indexing mechanism, to present an uncut portion of the blanks, separated by the proper distance from the portions last cut, for the action of the roughing broaches with which are associated said finishing broaches, at the next descent of their holder. Similarly the right-hand blanks are indexed upon the arrival at the upper end of its travel of the right-hand carrier 16. These operations continue until all of the teeth on the two stacks of blanks have been cut. During the last upward movement of the left-hand carrier, the associated lever 63 is actuated to cause the broaches in the holder mounted in said carrier to be thrown into neutral position;

and thus enable said broaches to descend inactively at the time the right-hand finishing broaches ascend to complete the last channel in the right-hand blanks. From the 5 above it is seen that it is necessary to cause the broaches carried by either holder to assume a neutral position at various times during the cutting operations, and more especially at the beginning and end of such 10 operations.

It is true that, in order to cause the broaches to assume their neutral positions, the offset 86 is removed from locking position beneath the lock-pin 87, but said offset is 15 out of such position only infrequently, for short periods of time, and while no cut is being made in the blanks on the holder above and consequently no force that might have a tendency to move the turn-table 112 20 on its axis is being exerted; moreover, the spring 123 is always present beneath said pin to hold the same normally in engaging relation with the shaft 117 above, and said shaft is also engaged by one of the yokes.

25 Meanwhile, stacks of ring-gear blanks are placed on the outermost holders, and are cured by means of the cam sleeve 126 and the clamps 141 and nuts 192 of said holders.

At the end of the gear-cutting operations 30 performed on the first two stacks of blanks, the levers 63 are operated to throw the broaches into neutral positions, and to displace the offsets 86 from beneath the heads 122. Next the yokes 148 with attached indexing parts and members are elevated by 35 means of the cranks 168, pinions 167, and racks 165, after first loosening the lock-screws 169. Then the treads 88 are operated to withdraw the lock pins 87 from 40 engagement with the turn-tables 112, and to raise said turn-tables, when each of the latter is given a half revolution on its shaft 113 to remove the newly-formed gears on the inner work holder from the cutting field, and 45 to carry into such field the new set or stack of blanks on the outer work holder. The turn-tables are now permitted to descend onto the base 1, and the yokes 148 are actuated downwardly onto the inner work 50 holders and the indexing members connected with said holders. Finally the nuts 192 and friction bars 135 are loosened and the clamps 141 removed, and the gears are taken 55 from the work holders which at this time are the outermost holders. The loading and unloading operations can not, of course, be performed at both ends of the machine at the same time by one operator, nevertheless, the machine can be handled by 60 a single operator in but little more time than would be required if the work were done by two operators.

First one lever 63 and then the other is actuated to cause the broaches controlled

thereby to be thrown out of the neutral into 65 the active position, and at the same time to throw the respective offsets 86 into locking positions.

It will have been observed that the axes of the broach holders and work holders are 70 fixed during the broaching operations—there is no feed of the broaches toward the work or of the work toward the broaches. This necessitates the use of roughing and finishing broaches capable by their combined action of finishing or completing a slot at each reciprocation of each broach holder.

The opening between the uprights 2 is continued downwardly through the base 1, as best shown at 191 in Fig. 2, and such 80 opening in said base is of sufficient length to permit the oil and chips from the cutting field above to drop down into the receptacle 5.

A single roughing broach and a single 85 finishing broach might be employed in each holder 26, but it is preferred to employ a plurality of each of such broaches in order that any replacement required can be more economically made, especially in the case 90 where it is necessary to employ comparatively long broach elements such as are used in this machine. By using a broach element made up of several sections or individual and separable units, it is a comparatively easy matter to remove a broken or damaged unit and replace it with a new one, moreover it is easier to grind the shorter units than it would be to grind the broach element if consisting of a single piece.

100 It is conceivable that the broaches might be so arranged that a complete gear-tooth slot is cut at each reciprocating movement of the broach holder.

The inner circumference of the blanks 139 105 is less than that of the supporting ring or flange 140, otherwise the friction bars 135 would encounter said flange and fail forcibly to engage said blanks. The required radial movement of the bars 135 is 110 comparatively slight.

By making changes in the work holders this machine can be used for broaching not only gears other than ring gears, but various objects that would not be classed as 115 gears, hence it is not intended to restrict the invention in this particular.

What we claim as our invention, and desire to secure by Letters Patent, is:—

1. In a broaching machine, independent 120 broach elements, means to reciprocate the same, and means to move them alternately into the work plane.
2. In a broaching machine, independent 125 broach elements, means to reciprocate the same, means to move them alternately into the work plane, and means to move them into neutral planes.

3. In a broaching machine, independent broach elements, means to reciprocate the same, automatic means to move them alternately into the work plane, and manually-controlled means to cause said second-named means to move said broach elements into neutral planes. 65
4. In a broaching machine, roughing and finishing broaches, means to reciprocate the same, and means to move them laterally and alternately into the work plane. 10
5. In a broaching machine, roughing and finishing broaches arranged in different radial planes, means to reciprocate said broaches, and means to move them alternately into the work plane. 15
6. In a broaching machine, roughing and finishing broaches arranged in sidewise relationship, means to reciprocate said broaches, and means to move them alternately into the work plane. 20
7. In a broaching machine, roughing and finishing broaches arranged in sidewise relationship, automatic means to reciprocate said broaches, and automatic means to move them alternately into the work plane. 25
8. In a broaching machine, roughing and finishing broaches, means to reciprocate the same, means to move them laterally and alternately into the work plane, and means to move them laterally into neutral planes. 30
9. In a broaching machine, roughing and finishing broaches arranged in sidewise relationship, automatic means to reciprocate said broaches, means to move them alternately into the work plane, and means to move them into neutral planes. 35
10. In a broaching machine, roughing and finishing broaches arranged in different radial planes, means to reciprocate said broaches, means to move them alternately into the work plane, and means to move them into neutral planes. 40
11. In a broaching machine, roughing and finishing broaches arranged in sidewise relationship, automatic means to reciprocate said broaches, automatic means to move them alternately into the work plane, and manually-controlled means to cause said second-named means to move said broaches into neutral planes. 45
12. In a broaching machine, constantly-reciprocating and intermittently-oscillating broach-carrying means. 50
13. In a broaching machine, a carrier, means to reciprocate said carrier, a broach holder mounted in said carrier, and means to oscillate said holder in said carrier. 55
14. In a broaching machine, a carrier, means to reciprocate said carrier, a holder mounted in said carrier and provided with radial roughing and finishing broaches, and means to oscillate said holder in said carrier. 60
15. In a broaching machine, a carrier, means to reciprocate said carrier, a broach holder mounted in said carrier, and means to oscillate said holder in said carrier at the ends of the travel of the carrier. 65
16. In a broaching machine, a carrier, means to reciprocate said carrier, a broach holder mounted in said carrier, and means to actuate said holder on its axis in said carrier in one direction when the carrier arrives at one end of its travel, and to actuate said holder on said axis in the opposite direction when the carrier arrives at the other end of its travel. 70
17. The combination, in a broaching machine, with a reciprocating carrier, and a broach holder mounted in said carrier, the latter being provided with oscillating means for said holder, of means in the paths of said oscillating means to operate the same at the ends of the travel of said carrier. 75
18. The combination, in a broaching machine, with a reciprocating carrier, and a broach holder mounted in said carrier, the latter being provided with oscillatory means for said holder, of movable means adapted to project into the paths of said oscillatory means and normally to cause the latter to be actuated at the ends of the travel of the carrier, and means partially to remove such projecting means from said paths. 80
19. The combination, in a broaching machine, with a reciprocating carrier, and a broach holder mounted in said carrier, the latter being provided with oscillatory means for said holder, of movable means adapted to project into the paths of said oscillatory means and normally to cause the latter to be actuated at the ends of the travel of the carrier, and manually-operated means partially to remove such projecting means from said paths, whereby the movement of said oscillatory means at the ends of the travel of the carrier are decreased. 85
20. The combination, in a broaching machine, with a reciprocating carrier provided with racks, and a broach holder mounted to oscillate in said carrier and having teeth in engagement with said racks, of cam members mounted in the paths of said racks, one of said members being at one end of one of said paths, and the other of said members being at the relatively opposite end of the other of said paths. 90
21. The combination, in a broaching machine, with a reciprocating carrier provided with racks, and a broach holder mounted to oscillate in said carrier and having teeth in engagement with said racks, of cam segments provided with teeth mounted in the paths of said racks, one of said segments being at one end of the path of one of said racks, and the other of said segments at the relatively opposite end of the path of the other of said racks, gears mounted 100
- 110
- 115
- 120
- 125

in intermeshing engagement with the teeth of said segments, and means to hold said gears stationary, and to actuate the same partially to remove said segments from said paths.

22. The combination, in a broaching machine, with a reciprocating carrier provided with racks, and a broach holder mounted to oscillate in said carrier and having teeth for engagement with said racks, of cam segments provided with teeth mounted in the paths of said racks, one of said segments being at one end of one of said paths, and the other of said segments being at the relatively opposite end of the other of said paths, suitably journaled shafts, gears secured to said shafts and intermeshing with the teeth of said segments, arms secured to said shafts, a connecting-rod between said arm, an operating lever for said rod, and locking means for said lever.

23. In a broaching machine, a reciprocating carrier, a holder for independent broach elements mounted to oscillate in said carrier, means to actuate said holder on its axis in one direction at one end of the travel of said carrier, and means to actuate said holder on its axis in the opposite direction at the other end of the travel of said carrier, and means to lock said holder against rotation during its intermediate travel in either direction.

24. In a broaching machine, a reciprocating carrier, a holder for roughing and finishing broaches mounted to oscillate in said carrier, means to actuate said holder on its axis in one direction at one end of the travel of said carrier, and means to actuate said holder on its axis in the opposite direction at the other end of the travel of said carrier, and means to lock said holder against rotation during its intermediate travel in either direction.

25. In a broaching machine, a reciprocating carrier, a holder for independent broach elements mounted to oscillate in said carrier, and means to actuate said holder on its axis into different positions.

26. In a broaching machine, a reciprocating carrier, a holder for independent broach elements mounted to oscillate in said carrier, means to actuate said holder on its axis into different positions, and means to lock said holder against rotation after the same is actuated into any of such positions.

27. In a broaching machine, a reciprocating carrier, a holder for independent broach elements mounted to oscillate in said carrier, means to actuate said holder on its axis into any one of three positions, and means to lock said holder against rotation after the same is actuated into any one of such positions.

28. In a broaching machine, a reciprocating

carrier, a holder for roughing and finishing broaches mounted to oscillate in said carrier, means to actuate said holder on its axis into any one of three positions, and means to lock said holder against rotation after the same is actuated into any one of such positions.

29. In a broaching machine, a reciprocating carrier, a holder for independent broach elements mounted to oscillate in said carrier, means to actuate said holder on its axis in one direction at one end of the travel of said carrier, means to actuate said holder on its axis in the opposite direction at the other end of the travel of said carrier, means to decrease the amount of actuation of said holder on its axis at either end of the travel of the carrier, and means to lock said holder against rotation during its intermediate travel in either direction.

30. In a broaching machine, a reciprocating carrier, a holder for roughing and finishing broaches mounted to oscillate in said carrier, means to actuate said holder on its axis in one direction at one end of the travel of said carrier, means to actuate said holder on its axis in the opposite direction at the other end of the travel of said carrier, means to decrease the amount of actuation of said holder on its axis at either end of the travel of the carrier, and means to lock said holder against rotation during its intermediate travel in either direction.

31. In a broaching machine, a reciprocating carrier, a broach holder mounted in said carrier, means to actuate said holder on its axis in one direction at one end of the travel of said carrier, means to actuate said holder on its axis in the opposite direction at the other end of the travel of said carrier, means to lock said holder against rotation during the intermediate travel, and means to unlock the same at each end of the travel before the operation of the oscillatory means takes place.

32. In a broaching machine, a reciprocating carrier, a broach holder mounted in said carrier, means to actuate said holder on its axis in one direction at one end of the travel of said carrier, means to actuate said holder on its axis in the opposite direction at the other end of the travel of said carrier, means to decrease the amount of actuation of said holder on its axis at either end of the travel of the carrier, means to lock said holder against rotation during the intermediate travel, and means to unlock the same at each end of the travel before the operation of the oscillatory means takes place.

33. The combination, in a broaching machine, with a reciprocating carrier, an intermittently-oscillating broach holder mounted in said carrier, and a perforated lock segment secured to said holder, of a lock pin

5 mounted in said carrier and adapted to enter any of the perforations provided in said segment for the reception of said pin, and means to withdraw said pin from said segment at the end of the travel in either direction of said carrier.

34. The combination, in a broaching machine, with a reciprocating carrier, an intermittently-oscillating holder mounted in said carrier, and a segment secured to said holder and perforated to receive a lock pin, of a spring-pressed lock pin mounted in said carrier and adapted to enter any of the perforations provided for the same in said segment, 10 a rock-shaft journaled in said carrier, an arm secured to said rock-shaft and in engagement with said pin, said arm being adapted to operate said pin, against the resiliency of its spring, to withdraw the same from locking engagement with said segment, a second arm secured to said rock-shaft, and members mounted in the path of travel of said last-named arm, at each end of such path, to actuate said arm and to 25 cause said pin to be disengaged from the segment.

35. The combination, in a broaching machine, with a reciprocating carrier, supporting means for said carrier, an intermittently-oscillating holder mounted in said carrier, and a segment secured to said holder and perforated to receive a lock pin, of a spring-pressed lock pin mounted in said carrier and adapted to enter any of the perforations provided for the same in said segment, a rock-shaft journaled in said carrier, an arm secured to said rock-shaft and in engagement with said pin, said arm being adapted to operate said pin, against the resiliency of its spring, to withdraw the same from locking engagement with said segment, a second arm secured to said rock-shaft, and cams mounted on said supporting means in the path of travel of said last-named arm, at each end 40 of such path, to actuate said arm and cause said pin to be disengaged from the segment.

36. The combination, in a broaching machine, with a reciprocating carrier, supporting means for said carrier, an intermittently-oscillating holder mounted in said carrier, and a segment secured to said holder and perforated to receive a lock pin, of a spring-pressed lock pin mounted in said carrier and adapted to enter any of the perforations provided for the same in said segment, a rock-shaft journaled in said carrier, an arm secured to said rock-shaft and in engagement with said pin, said arm being adapted to operate said pin, against the resiliency of its spring, to withdraw the same from locking engagement with said segment, a second arm secured to said rock-shaft, and spring-actuated cams pivotally connected with said supporting means, and

65 positioned in the path of travel of said last-named arm, at each end of said path, to cause said arm to be actuated and said pin to be disengaged from the segment, the springs of said cams being adapted to yield to enable the latter to be actuated out of the 70 way by said arm, and thus permit the same to return after it has caused the pin to be disengaged from the segment.

37. In a broaching machine, independent broach elements, and means to position said 75 elements sequentially in the work plane.

38. In a broaching machine, roughing and finishing broaches arranged in sidewise relationship and means to position said 80 broaches sequentially in the work plane.

39. In a broaching machine, independent broach elements, means to reciprocate said elements, means to oscillate the same into and out of the work plane, means to hold said elements positively against oscillatory 85 movement during their cutting operations, and means to release said elements for such movement at each end of each cutting operation.

40. In a broaching machine, roughing and finishing broaches arranged in sidewise relationship, means to reciprocate said broaches, means to oscillate the same into and out of the work plane, means to hold said broaches positively against oscillatory movement during their cutting operations, and means to release said broaches for such movement at 90 each end of each cutting operation.

41. In a broaching machine, independent broach elements, means to reciprocate said 100 broaches arranged in sidewise relationship, means alternately to actuate said elements into the work plane, means to actuate said elements into neutral planes, locking means to retain either of said elements in said work plane or both of said elements in said neutral planes during their intermediate reciprocating travel, and means to unlock or release said elements to the action of the actuating means at each end of said travel. 105

42. In a broaching machine, roughing and finishing broaches, means to reciprocate said broaches, means alternately to actuate said broaches into the work plane, means to actuate said broaches into neutral planes, locking means to retain either of said broaches in said work plane or both of said broaches in said neutral planes during their intermediate reciprocating travel, and means to unlock or release said broaches to the action of the actuating means at each end of said travel. 110

43. The combination, in a broaching machine, with a carrier, driving mechanism for said carrier, and an oscillatory broach 115 holder mounted in said carrier, of automatic means to reverse said mechanism at each end of the travel of said carrier.

44. The combination, in a broaching machine, with a carrier, driving mechanism for said carrier, and an oscillatory broach holder mounted in said carrier, of reversing means for said mechanism, said means consisting in part of a gear driven by said mechanism, said gear being provided with projecting members, and a switch-arm in the path of said members, and adapted to be actuated thereby first in one direction and then in the other.

45. In a broaching machine, a carrier, an oscillatory holder mounted in said carrier, independent broach elements, and means to secure said broach elements radially in said holder.

46. In a broaching machine, a carrier, a holder movably mounted in said carrier, bars having independent broach elements attached thereto and receivable in said holder and means to secure said bars to said holder.

47. In a broaching machine, a carrier, a holder movably mounted in said carrier, bars having independent broach elements attached thereto and receivable in said holder, and means to secure said bars and elements to said holder.

48. In a broaching machine, a carrier, a holder movably mounted in said carrier, bars, independent broach elements adapted to be carried by said bars, screws to secure said elements to said bars, the latter being receivable in said holder, and means to secure said bars to said holder.

49. In a broaching machine, a carrier, a holder movably mounted in said carrier, bars, independent broach elements adapted to be carried by said bars, screws to secure said elements to said bars, the latter being receivable in said holder, and means to secure said bars and elements to said holder.

50. In a broaching machine, a carrier, a holder movably mounted in said carrier, said holder being recessed, bars receivable in said recess, independent broach elements attached to said bars, and screws adapted to secure said bars and elements to said holder.

51. In a broaching machine, a carrier, a holder movably mounted in said carrier, said holder being recessed, bars having independent broach elements attached thereto, said bars being receivable in said recess, wedge blocks receivable in said recess between said elements, and bolts passing through said blocks and tapped into said holder.

52. In a broaching machine, a carrier, a holder movably mounted in said carrier, said holder being recessed, bars receivable in said recess and adapted to have independent broach elements attached thereto, screws adapted to attach said elements to said bars, and screws adapted to attach said bars and elements to said holder.

53. In a broaching machine, a carrier, a holder movably mounted in said carrier, said holder being recessed, bars adapted to have independent broach elements attached thereto and receivable in said recess, screws adapted to secure said elements and bars to said holder, wedge blocks in said recess, and bolts passing through said wedge blocks and tapped into said holder.

54. In a broaching machine, a carrier, a holder movably mounted in said carrier, said holder being recessed, bars receivable in said recess and adapted to have attached thereto independent broach elements, screws adapted to secure said elements to said bars, screws to secure said elements and bars to said holder, wedge blocks receivable in said recess between said elements, and bolts passing through said bars and tapped into said holder.

55. The combination, in a broaching machine, with upright supporting means, of carriers slidably arranged relative to said supporting means, oscillatory broach holders mounted in said carriers, and means for reciprocating said carriers in opposite directions.

56. The combination, in a broaching machine, with supporting means, of carriers arranged to slide up and down at opposite ends of said supporting means, means to reciprocate said carriers in opposite directions, broach holders mounted in said carriers, roughing and finishing broaches secured to said holders, and means to move said holders on their axes to carry one of the roughing broaches and one of the finishing broaches into the work plane at each end of the travel of said carriers.

57. In a broaching machine, a reciprocating carrier, an oscillatory holder mounted in said carrier, independent broach elements secured to said holder, means to actuate said holder to carry one of said elements out of and to position the other of said elements in the work plane at one end of the travel of said carrier, and means to actuate said holder to carry said second-named element out of and to carry said first-named element into said plane at the other end of said travel.

58. In a broaching machine, a reciprocating carrier, an oscillatory holder mounted in said carrier, roughing and finishing broaches secured to said holder, means to actuate said holder to carry said finishing broach out of and said roughing broach into the work plane at the end of the up stroke of said carrier, and means to actuate said holder to carry said roughing broach out of and said finishing broach into said plane at the end of the down stroke of said carrier.

59. The combination, in a broaching ma-

chine, with a reciprocating carrier, a broach holder mounted in said carrier, means to oscillate said holder, and manually-operated actuating and locking means to cause said oscillatory means to move said holder into neutral position, of a support, a turn-table above said support, work holders mounted on said turn-table, a lock pin for said turn-table, a locking member for said lock pin, and connecting means between said actuating means for said oscillatory means and said locking member.

60. The combination, in a broach holder, with a reciprocating carrier provided with racks, a broach holder mounted to oscillate in said carrier, and having teeth for engagement with said racks, cam segments in the paths of said racks, said segments having teeth, suitably mounted rock-shafts, gears secured to said rock-shafts and intermeshing with said segment teeth, arms secured to said rock-shafts, a connecting-rod between said arms, an operating lever for said connecting-rod, and locking means for said lever, of a support, a turn-table above said support, a lock-pin adapted to hold said turn-table against rotation, a rock-shaft having a part that is adapted when erect to prevent said pin from being withdrawn from locking position, an arm rigidly attached to said last-named rock-shaft, a suitably mounted bell-crank-lever, a connecting-rod between said last-named arm and said bell-crank-lever, and a connecting-rod between one of said first-named arms and said bell-crank-lever.

61. The combination, in a broaching machine, with independent broach elements, reciprocating means for said elements, and oscillatory means for said elements, whereby they are alternately actuated into the work plane, of a work holder arranged and adapted to position and carry the work through said plane.

62. The combination, in a broaching machine, with roughing and finishing broaches, reciprocating means for said broaches, and oscillatory means for said broaches, whereby they are alternately actuated into the work plane, of a work holder operatively positioned relative to such plane.

63. The combination, in a broaching machine, with independent broach elements, reciprocating means for said elements, and oscillatory means to actuate said elements alternately into the work plane, at the ends of the reciprocating movements thereof, of a work holder arranged and adapted to position and carry the work through said plane.

64. The combination, in a broaching machine, with roughing and finishing broaches, reciprocating means for said broaches, and oscillatory means to actuate said broaches alternately into the work plane, at the ends of

the reciprocating movements thereof, of a work holder operatively positioned relative to such plane.

65. The combination, in a broaching machine, with independent broach elements, reciprocating means for said elements, and movable means alternately to actuate said elements into the work plane, of a work holder arranged and adapted to position and carry the work through said plane, and means to index said holder during the stroke of the reciprocating means.

66. The combination, in a broaching machine, with roughing and finishing broaches, reciprocating means for said broaches, and movable means alternately to actuate said broaches into the work plane, of a work holder operatively positioned relative to such plane, and means to index said holder during the stroke of the reciprocating means.

67. In a broaching machine, a revoluble work holder, indexing means for said holder, independent broach elements, and means to actuate one of said elements in one direction through the work on said holder in the cutting field, and to actuate the other of said elements in the other direction through the work in said field, before the holder is indexed.

68. In a broaching machine, a revoluble work holder, indexing mechanism for said holder, independent broach elements, means to actuate said elements one after the other through the work on said holder in the cutting field, and means to index said holder each time after both of said elements have made their cuts in said work.

69. The combination, in a broaching machine, with a reciprocating carrier provided with a cam-block, and a broach holder movably mounted in said carrier, of a work holder, an index disk secured to said work holder, and operating means for said disk, said operating means consisting in part of a member in the path of said cam-block.

70. The combination, in a broaching machine, with a carrier provided with a cam-block, of a work holder, a serrated index disk secured to said work holder, a pivotally-mounted spring-pressed arm provided with teeth in normal engagement with the teeth on said disk, and having its free terminal in the path of said cam-block, said arm also being provided with a stud, a ratchet ring secured to said disk, and a pawl slotted to receive said stud and permit of a certain amount of independent movement between said stud and said pawl, said pawl being spring-pressed into engagement with said ratchet ring.

71. The combination, in a broaching machine, with a broach holder, of a turn-table, work holders mounted to rotate on said turn-table, and means to lock either of

said work holders in operative position relative to said broach holder.

72. The combination, in a broaching machine, with a reciprocating carrier, and a broach holder movably mounted in said carrier, of a turn-table, work holders mounted to rotate on said turn-table, means to lock either of said work holders in operative position relative to said broach holder, and means partially to rotate the work holder that is in operative position, at the end of each stroke in one direction of the broach holder.

73. The combination, in a broaching machine, with a reciprocating carrier, and a broach holder movably mounted in said carrier, of a turn-table, work holders mounted to rotate on said turn-table, means to lock either of said work holders in operative position relative to said broach holder, and means operated by said carrier at the end of each stroke in one direction thereof partially to rotate the work holder which is in such operative position.

74. In a broaching machine, a carrier, means to reciprocate said carrier, a broach holder mounted in said carrier, and means to move said holder in said carrier at the ends of the travel of the carrier.

75. The combination, in a broaching machine, with a reciprocating carrier, and a broach holder mounted in said carrier, the latter being provided with means to move said holder therein, of means in the paths of said moving means to operate the latter at the ends of the travel of said carrier.

76. In a broaching machine, a reciprocating carrier, a holder for independent broach elements mounted in said carrier, means to move said holder in one direction in said carrier at one end of the travel of the carrier, means to move said holder in the opposite direction in said carrier at the other end of the travel of the carrier, and means to lock said holder to said carrier during the intermediate travel of the same in either direction.

77. In a broaching machine, a reciprocating carrier, a holder for roughing and finishing broaches mounted in said carrier, means to move said holder in one direction in said carrier at one end of the travel of the carrier, means to move said holder in the opposite direction in said carrier at the other end of the travel of the carrier, and means to lock said holder to said carrier during the intermediate travel of the same in either direction.

78. In a broaching machine, a reciprocating carrier, a holder for independent broach elements movably mounted in said carrier, means to move said holder into any one of three positions in said carrier, and means to lock said holder to said carrier after the same is actuated into any of such positions.

79. In a broaching machine, a reciprocating carrier, a holder for independent broach elements movably mounted in said carrier, means to actuate said holder in one direction in said carrier at one end of the travel of the carrier, means to actuate said holder in the opposite direction in said carrier at the other end of the travel of the carrier, means to decrease the amount of actuation of said holder in said carrier at either end of the travel of the carrier, and means to lock said holder to said carrier during the intermediate travel of the same in either direction.

80. In a broaching machine, a reciprocating carrier, a broach holder mounted in said carrier, means to actuate said holder in one direction in said carrier at one end of the travel of the carrier, means to actuate said holder in the opposite direction in said carrier at the other end of the travel of the carrier, means to lock said holder to said carrier during the intermediate travel of the same, and means to unlock the holder at each end of the travel of said carrier.

81. In a broaching machine, a reciprocating carrier, a broach holder mounted in said carrier, means to actuate said holder in one direction in said carrier at one end of the travel of the carrier, means to actuate said holder in the opposite direction in said carrier at the other end of the travel of the carrier, means to decrease the amount of actuation of said holder in said carrier at either end of the travel of the carrier, means to lock said holder against independent movement relative to said carrier during the intermediate travel of the same, and means to unlock said holder at each end of the travel of the carrier.

82. In a broaching machine, independent broach elements, and means to position said elements alternately in the work plane.

83. In a broaching machine, roughing and finishing broaches arranged in sidewise relationship, and means to position said broaches alternately in the work plane.

84. In a broaching machine, independent broach elements, means to reciprocate said elements, means sequentially to move the same into and out of the work plane, means to hold said elements positively during their cutting operations, and means to release said elements at each end of each cutting operation.

85. In a broaching machine, independent broach elements, means to reciprocate said elements, means alternately to actuate the same into and out of the work plane, means to hold said elements positively during their cutting operations, and means to release said elements at each end of each cutting operation.

86. In a broaching machine, a carrier, a

- holder movably mounted in said carrier, independent broach elements, and means to secure said elements in vertical planes in said holder.
87. The combination, in a broaching machine, with upright supporting means, of carriers slidingly arranged relative to said supporting means, broach holders mounted in said carriers and adapted to be sequentially operated therein, and means for reciprocating said carriers in opposite directions. 70
88. The combination, in a broaching machine, with upright supporting means, of carriers slidingly arranged relative to said supporting means, broach holders mounted in said carriers and adapted to be alternately moved therein, and means for reciprocating said carriers in opposite directions. 75
89. In a broaching machine, a reciprocating carrier, a movable holder mounted in said carrier, independent broach elements secured to said holder, means to actuate said holder to carry one of said elements out of and position the other of said elements in the work plane at one end of the travel of said carrier, and means to actuate said holder to carry said second-named element out of and position said first-named element in said plane at the other end of said travel. 80
90. The combination, in a broaching machine, with independent broach elements, reciprocating means for said elements, and movable means for said elements, whereby they are alternately actuated into the work plane, of a revolute work holder arranged and adapted to position and carry the work through said plane. 85
91. The combination, in a broaching machine, with roughing and finishing broaches, reciprocating means for said broaches, and movable means for said broaches, whereby they are alternately actuated into the work plane, of a revolute work holder having its axis in such plane. 90
92. The combination, in a broaching machine, with independent broach elements, reciprocating means for said elements, and movable means to actuate said elements alternately into the work plane, at the ends of the reciprocating movements thereof, of a revolute work holder arranged and adapted to position and carry the work through said plane. 100
93. The combination, in a broaching machine, with roughing and finishing broaches, reciprocating means for said broaches, and movable means to actuate said broaches alternately into the work plane, at the ends of the reciprocating movements thereof, of a revolute work holder having its axis in such plane. 105
94. The combination, in a broaching machine, with independent broach elements, reciprocating means for said elements, and movable means alternately to actuate said elements into the work plane, of a revolute work holder arranged and adapted to position and carry the work through said plane. 110
95. The combination, in a broaching machine, with roughing and finishing broaches, reciprocating means for said broaches, and movable means alternately to actuate said broaches into the work plane, of a revolute work holder having its axis in such plane, and means to index said holder during the stroke in one direction only of the reciprocating means. 115
96. In a broaching machine, independent broach elements, means to position said elements alternately in the work plane, and means to position the work in said plane. 120
97. In a broaching machine, roughing and finishing broaches, means to position said broaches alternately in the work plane, and means to position the work in said plane. 125
98. In a broaching machine, independent broach elements, means to reciprocate the same, means to move them alternately into the work plane, and means to position the work in said plane. 130
99. In a broaching machine, independent broach elements, means to reciprocate said elements, means sequentially to move the same into and out of the work plane, means to hold said elements positively during their cutting operations, means to release said elements at each end of each cutting operation, and means to position the work in said plane. 135
100. In a broaching machine, independent broach elements, means to reciprocate said elements, means alternately to actuate the same into and out of the work plane, means to hold said elements positively during their cutting operations, means to release said elements at each end of each cutting operation, and means to position the work in said plane. 140
101. In a broaching machine, a carrier, a holder movably mounted in said carrier, independent broach elements, means to secure said elements in vertical planes in said holder, and means to position the work in operative position relative to said elements. 145
102. The combination, in a broaching machine, with independent broach elements, reciprocating means for said elements, and movable means for said elements, whereby they are alternately actuated into the work plane, of a work holder arranged and adapted to position and carry the work through said plane. 150
103. The combination, in a broaching machine, with independent broach elements, reciprocating means for said elements, and

movable means to actuate said elements alternately into the work plane, at the ends of the reciprocating movements thereof, of a work holder arranged and adapted to position and carry the work through said plane.

104. The combination, in a broaching machine, with independent broach elements, reciprocating means for said elements, and movable means alternately to actuate said elements into the work plane, of a work holder arranged and adapted to position and carry the work through said plane, and means to index said holder during the operation of the reciprocating means for said elements.

105. The combination, in a broaching machine, with independent broach elements, reciprocating means for said elements, and movable means alternately to actuate said elements into the work plane, of a work holder arranged and adapted to position and carry the work through said plane, and means to index said holder during the stroke in one direction only of the reciprocating means.

106. In a broaching machine, independent broach elements, means to reciprocate the same, means to move them alternately into the work plane, means to move them into neutral planes, and means to position the work in said work plane.

107. In a broaching machine, roughing and finishing broaches, means to reciprocate the same, means to move them alternately into the work plane, and means to position the work in said plane.

108. In a broaching machine, roughing and finishing broaches, means to reciprocate the same, means to move them alternately into the work plane, means to move them into neutral planes, and means to position the work in said work plane.

109. In a broaching machine, a carrier, means to reciprocate said carrier, a holder mounted in said carrier, and provided with radial roughing and finishing broaches, means to oscillate said holder in said carrier, and means to carry the work in operative position relative to said broaches.

110. In a broaching machine, a carrier, means to reciprocate said carrier, a broach holder mounted in said carrier, and means to move said holder in said carrier at the ends of the travel of the carrier.

111. In a broaching machine, a carrier, means to reciprocate said carrier, a broach holder mounted in said carrier, means to actuate said holder in said carrier at the ends of the travel of the carrier, and means to carry the work in operative position relative to said holder.

112. In a broaching machine, a carrier, means to reciprocate said carrier, a broach holder mounted in said carrier, means to ac-

tuate said holder in said carrier in one direction when the carrier arrives at one end of its travel, and to actuate said holder in said carrier in the opposite direction when the carrier arrives at the other end of its travel.

113. In a broaching machine, a carrier, means to reciprocate said carrier, a broach holder mounted in said carrier, means to actuate said holder in said carrier in one direction when the carrier arrives at one end of its travel, and to actuate said holder in said carrier in the opposite direction when the carrier arrives at the other end of its travel, and means to carry the work in operative position relative to said holder.

114. In a broaching machine, independent broach elements, means to position said elements sequentially in the work plane, and means to position the work in said plane.

115. In a broaching machine, roughing and finishing broaches, means to position said broaches sequentially in the work plane, and means to position the work in said plane.

116. The combination, in a broaching machine, with independent broach elements, reciprocating means for said elements, and movable means for said elements, whereby they are alternately actuated into the work plane, of a work holder adapted to position the work in said plane.

117. The combination, in a broaching machine, with independent broach elements, reciprocating means for said elements, and means to actuate said elements alternately into the work plane, at the ends of the reciprocating movement thereof, of a work holder adapted to position the work in said plane.

118. The combination, in a broaching machine, with independent broach elements, reciprocating means for said elements, and movable means alternately to actuate said elements into the work plane, of a work holder adapted to position and carry the work through said plane, and means to index said holder during the stroke of the reciprocating means.

119. In a broaching machine, a work holder, indexing means for said holder, independent broach elements, and means to actuate one of said elements in one direction through the work on said holder in the cutting field, and to actuate the other of said elements in the other direction through the work in said field, before the holder is indexed.

120. In a broaching machine, a work holder, indexing mechanism for said holder, independent broach elements, means to actuate said elements one after the other through the work on said holder in the cutting field, and means to index said holder

each time after both of said elements have made their cut in said work.

121. In a broaching machine, a carrier, means to reciprocate said carrier, a broach holder mounted in said carrier, means to move said holder in said carrier at the ends of the travel of the carrier, a work holder adapted to carry the work in operative position relative to said broach holder, and

means to index said work holder when said broach holder is moved in said carrier.
